SLIP DEVICE AND PACK-OFF TOOL

Elbert A. Rodgers, Altus, Okla.

Application September 24, 1956, Serial No. 611,431

3 Claims. (Cl. 166—121)

This invention relates to improvements in slip devices for use within pipe or tubing in drilled wells, which slip devices are used in connection with the holding of packers, pack-off members, and flow control devices at a predetermined position within a pipe or tubing within a well, until it is desired to remove the slip device from or to relocate it within the pipe or tubing.

The device as shown in the accompanying drawings, together with a modification thereof, shows a slip device and pack-off tool which is used to perform various functions, among which is the maintaining of a pack-off element, or a well flowing device within the tubing of an oil well while the fluid is being produced therethrough, and this device may be used in connection with holding such well flowing devices in flowing wells or in pumping wells at a desired position within the well tubing, which well flowing device is described in my co-pending application Ser. No. 605,006, filed August 20, 1956, for Liquid Level and Pressure Control Valve for Oil Wells.

Various tools for this purpose have been proposed heretofore, but these, for the most part, required considerable mechanism for the operation of the tool and to maintain the slips in locked position when set, and to enable the unlocking of the slips when it was desired to remove the tool from the well.

An object of the present invention is to provide a slip device which may be maintained in place without a special anchor rod, and without complementary dovetail grooving.

Another object of this invention is to provide a slip device wherein the slip may be readily removed from the device and new slip jaws inserted therein, and when once inserted in the tool, the slips cannot be dislocated unless the tool is disassembled.

Still another object of the invention is to provide a slip that will hold a tool, in the pipe or tubing, against movement in either up or down direction.

A still further object of the invention is to provide a slip that will hold a tool against movement in any direction until released.

With these objects in mind, and others which will become manifest as the description proceeds, reference is to be had to the accompanying drawings, in which like reference characters designate like parts in the several views thereof, in which:

Fig. 1 is an elevational view of a slip device and pack-off tool, showing a quarter section removed therefrom to show the details of construction, and showing the slips in engaged position, with a portion of a setting tool shown in dashed outline;

Fig. 2 is a sectional view taken on the line 2—2 of Fig. 1, looking in the direction indicated by the arrows;

Fig. 3 is a sectional view taken on the line 3—3 of Fig. 1, looking in the direction indicated by the arrows;

Fig. 4 is a sectional view taken on the line 4—4 of Fig. 3, looking in the direction indicated by the arrows;

Fig. 5 is a fragmentary elevational view of the upper portion of the tool with a quarter section removed, show-

2

ing the slips in retracted position, and showing a portion of a retrieving tool, in dashed outline, connected to the pack-off tool;

Fig. 6 is an elevational view showing the concave side of one of the slips apart from the tool, and which view is on a larger scale than shown in Figs. 1 and 5;

Fig. 7 is a view similar to Fig. 1, but of a modified form of the tool;

Fig. 8 is a sectional view taken on the line 8—8 of Fig. 7, looking in the direction indicated by the arrows, and being on an enlarged scale;

Fig. 9 is a sectional view taken on line 9—9 of Fig. 7, looking in the direction indicated by the arrows;

Fig. 10 is a sectional view taken on the line 10—10 of Fig. 7, looking in the direction indicated by the arrows;

Fig. 11 is a sectional view taken on the line 11—11 of Fig. 7, looking in the direction indicated by the arrows;

Fig. 12 is a view similar to Fig. 5, but of the modified form of the invention;

Fig. 13 is a perspective view of one of the slip elements shown apart from the tool; and

Fig. 14 is a view of the concave side of the slip, as shown in Fig. 13.

First form of invention

The invention, as shown in Figs. 1 through 6, has an elongated body portion 1, the lower end of which is reduced, as indicated at 2, to form a cylindrical portion to receive cups 4 and spacer elements 6 thereon. The lower end of the cylindrical portion 2 is threaded, as indicated at 8, to receive a nut 10 thereon, so as to cause spacer elements 6 to bindingly engage cups 4 between the spacer elements and between the uppermost spacer element and the shoulder 12 on the body 1, which cups are adapted to seat within a pipe, tubing or seating nipple, in a manner well understood in the art of packers, and as is fully brought out in the above identified co-pending application.

The body portion 1 is flattened, as indicated at 14, so as to enable the gripping thereof with holding tools, for assembly and disassembly, as is well understood in the art. The intermediate portion of the body 1, between the flattened portion 14 and the upper end 16, is tapered, as indicated at 18. The taper is preferably conical in shape, and is adapted to complementarily receive slips, which are designated generally at 20, thereon in peripheral, spaced relation within a cage 22.

The slips 20 have end portions 24, which extend from each end thereof into a recess formed within the bore of cage 22, which will retain the slips within the cage, unless the cage is removed from the body portion 1. The lower end portions of the slips are tapered downwardly and inwardly, as indicated at 26, and interfit in complementary, sliding relation with a downwardly and inwardly sloping portion of the cage 22, so when the cage 22 moves upward, the slips will move from the position as shown in Fig. 1 to that shown in Fig. 5.

The concave portion of each of the slips is such as to fit the conical taper 18 of the body, when in the lowest position, but when the slips are moved into the upper position, as shown in Fig. 5, the taper on the conical taper 18 and the taper of the end portion 16 will be of lesser diameter than the concave portion 30 of the slips, which will permit the slips to slide freely without binding. The cage 22 has slotted openings 32 therein, through which the slips 20 project, but which slips are retained against loss by end portions 24.

While any pattern of teeth, on the slips, may be used as desired, it is preferable to have the teeth 34 turned in one direction on one end of the slips, and the teeth

36, on the other end of the slips, turned in the opposite direction, so as to maintain the pack-off tool against movement in either direction. The upper end portion 16, of the body 1, has an annular groove 38 formed near the upper end thereof, which groove receives a clip ring 40 therein, which ring 40 serves as a lock ring, so as to maintain the cage 22 on the reduced end portion 16 of the body 1. The cage 22 has an elongated neck 42 which extends upwardly from the body portion thereof, and has a shoulder 44 formed near the upper end thereof, the purpose of which will be explained in detail hereinafter. The upper end of the neck portion 42 has a recessed portion 46 therein to complementarily engage clip ring 40, as will best be seen in Fig. 5, which recess serves to prevent the clip ring 40 from spreading, while the tool is being removed from the well, as will be brought out more in detail hereinafter.

The body portion 1 has an axial bore 52 therethrough which bore is threaded, as indicated at 48 and 50 at the lower and upper ends respectively, which threaded portions enable the connecting of pipe thereto, as will be brought out more in detail hereinafter. The axial bore 52 permits the passage of fluid therethrough, as is fully brought out in the above identified application.

The present tool may be used to perform various functions such as maintaining a bottom hole choke in place at the lower end of the tubing, maintaining a well flowing device in place, as set forth in the above identified co-pending application, and for such other uses as slip devices and pack-off tools are employed.

The device may be set at a particular location within a tubing, pipe, or seating nipple by lowering the slip device and pack-off tool into the well by the use of a setting tool 54. Setting tools are of varied design and common in the art, therefore, no specific setting tool will be set forth, except that the tool is shouldered, and that the shoulders thereof engage below clip ring 40 to lower the tool thereby, to the desired depth, whereupon, a pull upon the wire line, to which the setting tool 54 is attached, will cause the teeth 34 and 36 of the slips 20 to bite into the wall of the tubing, pipe or seating nipple, as the case may be, so as to hold the slip and pack-off device against movement in either direction, and with the cups 4 seating against the wall of the pipe or tubing, fluid pressure is maintained below the cups, which pressure is forced to pass upward through axial bore 52, and through any tool or flow device which is connected thereto.

Occasionally it is desirable to seat the tool into a pipe or tubing by means of a pipe or rod, to prevent the tool from being blown from the well, in which event, the pipe or rod is screwed into threaded connection 50, and the tool is lowered to the particular position in the tubing desired, then a sudden upward pull is given to the pipe or rod, which will lock the teeth 34 and 36 within the tubing of the well, whereupon, the pipe may be unscrewed from the threaded connection 50 and removed. The threads 50 may be either right or left hand threads, but if a right hand threaded string of pipe is used, it is preferable that the threads of the connection 50 be left hand threads. However, if the threads of the member 50 are right hand threads, and the threads on the setting pipe are right hand threads, the pipe engaging the threads need not be made up tight on the pipe, which will enable the unscrewing of the pipe without loosening the intermediate threaded joints of the setting pipe.

It is also desirable, at times, to produce oil separately from different strata in the well, therefore, with a pack-off tool as shown herein, a seal may be made within the tubing intermediate the producing zones, and a string of pipe screwthreaded into screwthreaded connection 50 to enable the flowing of the fluid below the cups to the top of the well. However, the tubing above the cups 4 may be perforated, and oil or gas flowed to the top of the well separately and independently of the fluid being

flowed up in the pipe connected to the threaded connection 50.

With the slips 20 each having certain of the teeth 34 turned in one direction and certain of the teeth 36 turned in the opposite direction, the slip device and pack-off tool is maintained against movement by pressure, in an upward direction, as the reaction on cups 4, by pressure, will move tapered member 18 upward to cause the slips 20 to move outward. However, any weight applied above cage 22, will cause the teeth 36 to maintain the tool against moving downward. If the slip device and pack-off member has been set by a wire line, the setting tool may be removed therefrom in a conventional manner, such as by a three-count ratchet disconnect device, which will disengage the tool and leave it set as the desired level.

When it is desired to remove the pack-off tool from the tubing, a removing tool, having jaws 56, is designed to slip over enlarged end shoulder portion 44, so as to engage below the shoulder 44, as shown in dashed outline in Fig. 5, whereupon, a sudden upward pull will cause the lower tapered portion 28 of cage 22 to act against the tapered portion 26 of the slips 20, which will urge the slips upward, and since the taper is of reduced size, the slips will move inward from the position as shown in Fig. 1 to that shown in Fig. 5, thereby enabling the tool to be readily removed from the well, as the upper end portion 42 of the cage 22 engages below clip ring 40 to move the body portion 1 upward, together with the cups and other apparatuses or elements connected therewith. The annular recess 46 surrounds clip ring 40 and prevents this ring from spreading.

A pipe may be screw threaded into threaded connection 48 and to a well flowing device, such as described in the above entitled co-pending application, or such other device as a bottom hole choke, oil and gas separator or the like may be connected thereto.

Modified form of invention

The form of the invention, as shown in Figs. 7 through 14, is so constructed that, when once set, the teeth of the gripping slips will grip the inside of the pipe, tubing or the like, so as to prevent the movement of the holding tool in any direction, up, down or in a rotary movement relative to the tubing.

The invention, as disclosed in Figs. 7 through 14, has an elongated body portion designated generally at 1, and which has the lower end thereof reduced, in substantially the same manner as is the elongated body of the aforementioned form of the invention. In fact, the entire body assembly, comprising the elongated body 1, reduced end portion 2, cups 4, and spacer elements 6, is substantially identical with the aforementioned form of the invention. The lower reduced end portion of body 1 is threaded, as indicated at 8, to receive a nut 10 thereon.

When the cups 4 and spacer elements 6 are assembled and secured in place by means of nut 10, a packing unit is formed, which seats within the inside of a seating nipple or tubing to form a seal therewith.

The elongated body 1 has a shoulder 12 thereon for the uppermost of the cups to seat against. A flattened portion 14, is provided on the body 1, which enables a wrench to be fitted thereon for holding the body portion against relative rotation, upon turning nut 10.

The upper end portion of the body 1 is reduced, as is indicated at 16, with a tapered portion 18 intermediate the enlarged portion of the body and the reduced end portion 16. Slips, designated generally at 70, interfit within round holes 82 formed within cage 72. The holes 82, formed in the cage 72, are circumferentially spaced therearound and each of the holes has the axis thereof lying within a longitudinal plane radiating from the axis of cage 72, which cage is coaxial with the body

1. The axis of the holes 82 slope downwardly and inwardly toward the axis of body 1 and are of the same complementary angle of the slope of axis of slips 70. The portion of the slips 70 which project through the respective holes 82, is complementary with respect to the hole, so the slips will have a normal tendency to fall, by gravity, from the position as shown in Fig. 7, to the position as shown in Fig. 12, when the cage 72 is moved upward. The body portion of each slip has a projection 74 above and below and on each side of the cylindrical body portion of the slip. The inside portion of each slip is concave, as indicated at 80. The concave portion 80 is in complementary fitting relation with the taper 18 on body 1, when the cage 72 is in the lowermost position, as shown in Fig. 7. However, when the cage is in the uppermost position, as shown in Fig. 12, the slips 70 will move inward so that the teeth 84 will retract within the outer cylindrical confines of cage 72.

The form of the invention, as shown in Figs. 7 through 14, preferably has two or more rows of circumferentially arranged slips, the slips of one row being staggered longitudinally with respect to the slips in the adjacent row, as shown in Figs. 7, 8, 9, and 12, with the teeth 84 preferably being in the form of a pyramid, which tends to hold the tool against movement in any direction, when the teeth are properly set.

With the holes 82, in the cage, being drilled at an angle to slope inwardly and downwardly, the slips will readily retract when the cage 72 is moved upward.

The other component parts of the tool, together with the manner of setting thereof and removing same are substantially the same as for the form shown in Figs. 1 through 5, and described above, with the exception that the slips and the complementary portion of the slip holding cage.

Setting and removing operation

To set the slip device and pack-off element in a well having tubing, pipe, or a seating nipple therein, and with a flow device, or the like, connected thereto by threaded connection 48, the device may be lowered into the well on a wire line lowering tool 54, or it may be lowered on the end of a rod screwed into threaded connection 50 in axial bore 52, whereupon, if a rod or threaded pipe is used for lowering the slip device and pack-off element into the well, and after the device is set, the pipe or rod may be unscrewed, in the same manner as in the aforementioned form of the invention. To remove the slip device and pack-off element, a tool having prongs 56 thereon, of such size and shape as to engage shouldered portion 44, is lowered into the well on a wire line, pipe or rod, whereupon, the prongs 56 engage below shouldered portion 44 so that the cage is moved upward until the slips 70 recede inward on tapered portion 18 of the body 1, until the slip teeth 84

disengage from the inner wall of the tubing, seating nipple or the like.

Having thus clearly shown and described the invention, what is claimed as new, and desired to be secured by Letters Patent is:

1. A well device, including an elongated, main body portion, the intermediate portion of said body portion being of a general cylindrical configuration and of larger diameter than the adjacent portions of said main body portion, the lower portion of said body portion of larger diameter intermediate portion and the lower end thereof being cylindrical in shape, which cylindrical portion is adapted to receive packing cups and spacers thereon, threaded means threadably engaging said lower cylindrical portion to hold said cups in binding relation upon said cylindrical body portion, said body portion intermediate said portion of larger diameter and the upper end of said main body being tapered for a portion of the length thereof, the portion of said body above said tapered portion being cylindrical, slip members fitted in complementary relation on the tapered portion of said body, the body portion of said slip members being substantially cylindrical in shape and having the respective axes thereof lying within longitudinal planes, the axes of which converge inwardly and downwardly, the cylindrical body portion of each of said slip members having outwardly projecting teeth thereon, an apertured cage telescoped over said cylindrical upper end portion of said body in complementary sliding relation, a portion of said cage having lateral, cylindrical apertures formed therein, the axes of which apertures converge inwardly and downwardly, said last mentioned portion of said cage fitting over said tapered portion of said body, said cylindrical portion of said slip members extending through the respective lateral apertures in said cage in complementary sliding relation with respect thereto so that said slips extend out through apertures in said cage, stop means on said upper cylindrical portion of said body intermediate said tapered portion and the end of said cylindrical portion, to arrest the upward movement of said cage at a predetermined position.
2. The device as defined in claim 1, wherein said cage has a multiplicity of apertures formed therein in offset longitudinal relation with respect to certain other apertures formed therein.
3. The device as set forth in claim 1, wherein said teeth of said slips are pyramidal in form.
